VALVE FOR RESPIRATORY DEVICES

Bradford B. Holmes, New York, N. Y., assignor to
 Bendix Aviation Corporation, Teterboro, N. J.,
 a corporation of Delaware

Application June 18, 1946, Serial No. 677,598

8 Claims. (Cl. 251—34)

1

This invention relates to respiratory devices, and more particularly to a diluter valve for a demand regulator.

An object of my present invention is to provide a diluter valve for a demand regulator whereby the mixture ratio of a gas under pressure, as for example oxygen, and of a second gas, such as air, may be adjusted.

Another object of this invention is to provide a diluter valve for a demand regulator in which a gas is entrained in a venturi by a second gas under pressure flowing therein from a jet or nozzle; the gas to be entrained entering through said diluter valve, the quantity of which is regulated by a spring biased, beveled plug therein.

A further object of my invention is to provide a diluter valve for a demand regulator wherein the position occupied by the beveled plug in the inlet thereof is adjusted by a knob; the mixture ratio of the gases being predetermined and set as by detents for said knob to indicate and hold the same in one position for a particular mixture ratio.

Still another object of the invention is to provide a highly improved and compact diluter valve of the character described which shall be of simple operation, relatively inexpensive to manufacture, positive in action, which shall have a large variety of applications, and yet be practical and efficient to a high degree in use.

Other objects of the invention will in part be obvious, and in part hereinafter pointed out.

The invention accordingly consists in the features of construction, combinations of elements, and arrangement of parts which will be exemplified in the construction hereinafter described, and of which the scope of application will be indicated in the appended claims.

In the accompanying drawings, in which one of the various possible illustrative embodiments of this invention is shown,

Fig. 1 is a cross-sectional view with portions shown in elevation of a diluter valve incorporated into the body of a demand regulator.

Fig. 2 is a schematic drawing of a demand regulator and the improved diluter valve, illustrating the operation thereof, while

Fig. 3 is a top plan view of the diluter valve knob.

Referring in detail to Figs. 1 and 2 of the drawings, 10 designates a diluter valve embodying the present invention, incorporated into the body of a demand regulator 11. The regulator 11 comprises a cylindrical body 12 provided with an inlet 13 and an outlet 14. The inlet 13 is adapted

2

to be connected to a source of oxygen under pressure (not shown); while the outlet 14 is adapted to be connected by means of a hose line to a respiratory mask (not shown).

5 The cylindrical body 12 of the regulator is provided with a bottom plate 14 and a top cover plate 15, said cover being provided with an opening 16. Fixed over the open end of the body portion 12 and under cover plate 15, is a diaphragm 17 provided with a metal plate 18. Depending from said plate is a stud 19, to the lower end of which is pivoted a lever 20. The lever 20 is pivoted at its opposite end in a suitable manner (not shown) to the body 12 of the regulator. The lever 20 is provided with an abutment member 21 adapted to open and close a demand valve 22.

10 The demand valve 22 is located within the body of the demand regulator 11 and is placed in the oxygen pressure line. The valve comprises a chamber 23, a valve member 24 and a valve seat 25. The valve member 24 is adapted to abut the valve seat 25 due to the action of a coil spring 26 and to be opened against the action of the spring 26 by reason of the abutment of lever 20 15 against a valve stem 27 fixed to said valve member.

20 Referring now to Fig. 2, the inlet 13 is connected to the demand valve 22 through a pressure reducing valve 28. The pressure reducing valve 28 comprises a chamber 29 within the body 12 of said regulator and has therein disposed a pressure responsive member 30. Fixed to said pressure responsive member is a stem 31. Pivoted on stem 31 is a linkage system 32 for actuating a valve member 33. The valve member 33 is adapted to abut a valve seat 34 formed in the inlet line 13.

25 The pressure responsive member 30 is adapted to open the valve 34 at a predetermined pressure and to close the valve at a second predetermined higher pressure. Thus, the oxygen flowing through the inlet line 13 is permitted to enter the chamber 29 and cut off when the pressure within the chamber 29 reaches the predetermined higher pressure.

30 In the use of the regulator, the inspiration of the mask wearer will lower the pressure within the regulator body 12. Due to the decrease in pressure, the diaphragm 17 will collapse, pivoting the lever 20 in a counterclockwise direction. Counterclockwise movements of the lever 20 will cause the valve stem 27 to move in a downward direction to open the demand valve 22. The oxygen will then be permitted to flow from the pressure reducing valve 28 through chamber 29 into a

line 36. The line 36 terminates in an injector nozzle 37. The stream of oxygen flowing from the injector nozzle 37 is directed into a venturi 38 which leads to the outlet 14.

The demand regulator hereinbefore described is more adequately illustrated and described in my co-pending application bearing Serial No. 482,016 filed on April 6, 1943, wherein a similar type of regulator is illustrated.

Means is provided to dilute the oxygen passing through the regulator with predetermined quantities of air so that the air finally delivered to the mask connected to the regulator will have stated percentages of oxygen added thereto.

To this end the diluter valve 10 embodying the present invention is incorporated into the body of the regulator. The diluter valve assembly 10 is inserted into the side of the regulator body 12, registering with a chamber 40 formed therein by walls 41 and 42. The valve assembly is fixed to said body as by a plate 43 fastened thereto in a suitable manner. A resilient gasket 44 placed between the plate 43 and the ends of the walls 41 and 42 seals the chamber 40 from outside pressures.

Fixed to the plate 43 by screws 46, is a cylindrical, cup-shaped member 45; a resilient gasket 47 forming a seal between the two members. The cylindrical member 45 is formed with an inwardly extending sleeve 46 concentric with said member. Said member is further provided with a valve seat 47 extending outwardly from the bottom of said member and concentric with the sleeve 46. Spring urged against said seat by a coil spring 48 is a valve 49. The outer end of the spring 48 abuts against a spring retainer 50, said spring retainer comprising four arms 51, two of which are shown; the ends of which are retained in a peripheral groove 52 cut into the member 45 adjacent to the valve seat 47. The valve mechanism described will hereinafter be referred to as the check valve 49.

Slidably received within the sleeve 46 is a plug 55 having a beveled portion 56 within the sleeve 46, a shoulder 57 provided with a sealing gasket 58 adapted to abut the end of the sleeve 46; and a spring shoulder 59. About said plug and the sleeve 46, and between the shoulder 59 and the cylindrical member 45, is a coil spring 60; said spring tending to move the beveled portion of said plug out of the sleeve 46. The upper or outer end of said plug is formed with an annular recess 61.

For the purposes hereinafter appearing, the cylindrical member 45 is provided with a small longitudinally extended opening 65. Placed within said opening is a small coil spring 66 and a ball 67, said spring urging said ball in an outward direction. The cylindrical member 45 is further provided with a plurality of ports 68 which permit the air to enter the chamber 69 formed by said cylindrical member.

Fixed to the cylindrical member 45, as by rivets 70, is a plate 71; said plate being formed with an opening 72 into which the ball 67 fits and is retained thereby. Wedged to the plate 71 are four upright posts 75, three of which are shown in the drawings. Slidably mounted over the posts 75 is a spider 76 formed with three radially extending lugs 77, one of which is indicated. The spider 76 is formed with an extended sleeve portion 78, said sleeve portion extending into the recess 61 of the plug 55.

Rotatably mounted on plate 71 is a setting knob 80, said knob being held in place on said plate by

a clamping ring 81 fixed to the cylindrical member 45 in a suitable manner. The clamping ring 81 is provided with openings 82 which register with the openings 68 in the cylindrical member

5 45. The setting knob 80 is provided with a knurled exterior surface 83 and a threaded interior surface 84, said interior surface comprising three square cut threads, each of said threads being adapted to coact with a lug 77 on the spider 10 71. Fixed to the top of the setting knob by screw 86 and nut 87, is an indicating dial 98; the markings of which are illustrated in Fig. 3. The bottom edge of the setting knob 80 resting on the plate 71 is provided with a plurality of detent 15 openings 91, one of which is illustrated in Fig. 1. In the present application five detent openings spaced about the perimeter of the setting knob 80 are provided to give five setting positions for the knob 80.

20 The diluter valve assembly 10 illustrated in Fig. 1 is shown with the spider 76 in its lowermost position. The plug 55 is in its lowermost position so that the gasket 58 of shoulder 57 abuts the end wall of the sleeve 46. The interior of the sleeve 25 46 is thus sealed from the chamber 69 formed within the cylindrical member 45, so that no air which enters through the ports 68 may enter the sleeve 46. Rotation of the setting knob 80 will cause the spider 76 to be moved away from the plug 55 by virtue of the engagement of the lugs 77 thereon with the threads 84 in said knob. The tension of spring 60 being relieved will move the plug 55 to open the end of the sleeve 46, permitting the air from chamber 69 to enter said 30 sleeve. The air in sleeve 46 will then pass through the check valve 49 to enter the chamber 40 within the body of the regulator 11.

The chamber 40 is adjacent to the injector nozzle 37 of the regulator as illustrated in the schematic of Fig. 2. The velocity of the oxygen passing through said nozzle will entrain the air of chamber 40 in the venturi 38, mixing the two gases. The oxygen-air mixture is pulled out through the outlet 14 by the inspiration of the 45 mask user. The check valve 49 prevents the exhalation of the user, or oxygen, from entering the sleeve 46.

The mixture ratio of oxygen and air may be varied by varying the size of the opening between the beveled face 56 of the plug 55, and the sleeve 46. The rotation of the setting knob 80 will move the spider 76 along the posts 75 to permit the spring 60 to move said plug away from the end of the sleeve 46. The detent openings previously described in the knob 80 are set for a predetermined mixture ratio. In the instant application the setting knob 80 has been illustrated as having five positions. The position "20," or 20% added oxygen, is the first position of the knob 80. In this position the beveled face 56 of the plug 55 is completely withdrawn from the sleeve 46. The position indicated as "100," being 100% oxygen, is illustrated in Fig. 1 with the sleeve 46 sealed against the air in chamber 69. The indicated percentages on the knob 80 will, when registering with an index 93 marked on plate 43, position the plug at intermediate points within the sleeve 46 between these two extremes.

70 It will thus be seen that there is provided a diluter valve assembly in which the several objects of this invention are achieved and which is well adapted to meet the conditions of practical use. While the foregoing description has been limited to the mixture of oxygen with air, it is

obvious that other gases may be mixed in the manner and with the apparatus described.

As various possible embodiments may be made of the above invention and as various changes may be made in the embodiment above set forth, it is to be understood that all matter herein set forth or shown in the accompanying drawings is to be interpreted as illustrative and not in a limiting sense.

Having thus described my invention, I claim as new and desire to secure by Letters Patent:

1. A diluter valve comprising a chamber, at least one fluid entry port in the side walls of said chamber, a centrally disposed outlet port in the bottom wall of said chamber, a sleeve longitudinally fixed within said chamber and registering with the outlet port therein, a plurality of parallel posts, a spider slidably received on said posts, a setting knob rotatably mounted on said chamber and receiving said posts and spider, a threaded interior surface in said knob coacting with said spider to move said spider along said posts, a plug longitudinally disposed within said cylindrical member, a beveled surface at one end of said plug adapted to be received within said sleeve, and resilient means adapted to bias said plug away from said sleeve and against said spider, the rotation of said knob moving said spider and said plug to vary the opening between the beveled surface and said sleeve to control the fluid flow through said sleeve.

2. A diluter valve comprising a chamber, at least one fluid entry port in the side walls of said chamber, a centrally disposed outlet port in the bottom wall of said chamber, a sleeve longitudinally fixed within said chamber and registering with the outlet port therein, a plurality of parallel posts, a spider slidably received on said posts, a setting knob rotatably mounted on said chamber and receiving said posts and spider, a threaded interior surface in said knob coacting with said spider to move said spider along said posts, a plug longitudinally disposed within said chamber, a beveled surface at one end of said plug adapted to be received within said sleeve, a shoulder on said plug adapted to abut the end of said sleeve to seal the same, and resilient means adapted to bias said plug away from said sleeve and against said spider, the rotation of said knob moving said spider and said plug to vary the opening between the beveled surface and said sleeve to control the fluid flow through said sleeve.

3. A diluter valve comprising a cylindrical cup-shaped member, a plurality of fluid entry ports in the side walls of said member, a centrally disposed opening in the bottom wall of said member, a sleeve longitudinally fixed within said member and registering with the centrally disposed opening therein, a plurality of parallel posts, a spider slidably received on said posts, a setting knob rotatably mounted with said member and receiving said posts and spider, a threaded interior surface in said knob coacting with said spider to move said spider along said posts, a plug longitudinally disposed within said cylindrical member, a beveled surface at one end of said plug adapted to be received within said sleeve, and resilient means adapted to bias said plug away from said sleeve and against said spider, the rotation of said knob moving said spider and said plug to vary the opening between the beveled surface and said sleeve for controlling the fluid flow from said plurality of ports in said cylindrical cup-shaped member through said sleeve.

4. A diluter valve comprising a cylindrical cup-

shaped member provided with a plurality of fluid entry ports in the side walls thereof and a centrally disposed opening in the bottom wall thereof, a sleeve longitudinally fixed within said member and registering with the centrally disposed opening therein, a plurality of parallel posts, a spider slidably received on said posts, a setting knob rotatably mounted with said member and receiving said posts and spider, a threaded interior surface in said knob coacting with said spider to move said spider along said posts, a plug longitudinally disposed within said cylindrical member, a beveled surface at one end of said plug adapted to be received within said sleeve, a shoulder on said plug adapted to abut the end of said sleeve to seal the same, and resilient means adapted to bias said plug away from said sleeve and against said spider, the rotation of said knob moving said spider and said plug against the action of said resilient means to vary the opening between the beveled surface and said sleeve for controlling the fluid flow from said plurality of ports in said cylindrical cup-shaped member through said sleeve.

5. A diluter valve comprising a cylindrical cup-shaped member provided with a plurality of fluid entry ports in the side walls thereof and a centrally disposed opening in the bottom wall thereof, a sleeve longitudinally fixed within said member and registering with the centrally disposed opening therein, a circular plate fixed to the open end of said member, an opening in said circular plate registering with the open end of said member, a plurality of parallel posts fixed to said plate, a spider slidably received on said posts, a setting knob rotatably mounted on said circular plate, receiving said posts and spider, a threaded interior surface in said knob coacting with said spider to move said spider along said posts, a plug longitudinally disposed within said cylindrical member, a beveled surface at one end of said plug adapted to be received within said sleeve, a shoulder on said plug adapted to abut the end of said sleeve to seal the same, and resilient means adapted to bias said plug away from said sleeve and against said spider, the rotation of said knob moving said spider and said plug against the action of said resilient means to vary the opening between the beveled surface and said sleeve for controlling the fluid flow from said plurality of ports in said cylindrical cup-shaped member through said sleeve.

6. A diluter valve comprising a cylindrical cup-shaped member provided with a plurality of fluid entry ports in the side walls thereof and a centrally disposed opening in the bottom wall thereof, a sleeve longitudinally fixed within said member and registering with the centrally disposed opening therein, a circular plate fixed to the open end of said member, an opening in said circular plate registering with the open end of said member, a plurality of parallel posts fixed to said plate, a spider slidably received on said posts, a setting knob rotatably mounted on said circular plate, receiving said posts and spider, a threaded interior surface in said knob coacting with said spider to move said spider along said posts, a plurality of detents for said knob, a plug longitudinally disposed within said cylindrical member, a beveled surface at one end of said plug adapted to be received within said sleeve, a shoulder on said plug adapted to abut the end of said sleeve to seal the same, a second shoulder on said plug, and a coil spring placed about said plug and said sleeve between

the second shoulder on said plug and the bottom wall of said cylindrical cup-shaped member adapted to bias said plug away from said sleeve and against said spider, the rotation of said knob moving said spider and said plug against the action of said spring to vary the opening between the beveled surface and said sleeve for controlling the fluid flow from said plurality of ports in said cylindrical cup-shaped member through said sleeve.

7. A diluter valve comprising a chamber, at least one fluid inlet port for said chamber, a fluid outlet port for said chamber, a sleeve fixed in said chamber and registering with said outlet port, a plurality of posts parallel with said sleeve, a spider slidably mounted on said posts, a beveled plug slidably receivable within said sleeve, resilient means tending to bias said plug out of said sleeve and into engagement with said spider, and means for moving said spider whereby said plug is moved against the action of said resilient means to position the same within said sleeve to vary the opening in said sleeve for controlling the fluid flow therethrough.

8. A diluter valve comprising a chamber, at least one fluid entry port for said chamber, a fluid outlet port for said chamber, a sleeve fixed in said chamber and registering with said outlet port, a plurality of posts parallel with said

sleeve, a spider slidable on said posts, a plug provided with a beveled surface thereon slidably received within said sleeve, a shoulder on said plug back of said beveled surface and adapted to abut the free end of said sleeve to close said outlet port, and resilient means tending to bias said beveled surface out of said sleeve and into engagement with said spider, said spider being movable on said posts for moving said plug against the action of said resilient means to position said beveled surface within said sleeve to vary the opening between said surface and said sleeve, the opening of said sleeve decreasing as the beveled surface advances into said sleeve until said shoulder abuts the end of said sleeve to close the outlet port.
